ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

LOCK.

1,169,184.

Specification of Letters Patent.

Patented Jan. 25, 1916.

Application filed December 4, 1913. Serial No. 804,638.

To all whom it may concern:

Be it known that I, ALBERT A. PAGE, a citizen of the United States, residing in the town of East Haven, county of New Haven, 5 and State of Connecticut, have invented certain new and useful Improvements in Locks, of which the following is a full, clear, and exact description.

This invention relates to locks, and more 10 particularly to the locks for the communicating doors of hotel rooms.

The primary object of the invention is to provide a lock in which the two customary independent thumb bolts operable from the 15 respective sides of the door may be retracted simultaneously with a key bolt, which is only operable by a chamber-maid, bell boy, or other authorized person, in possession of a proper key. The door may be locked by 20 the key bolt, so that the manipulation of either or both of the thumb bolts will be of no effect in opening the door, and when the key bolt is retracted by an authorized person each thumb bolt which is in protracted 25 position will be retracted simultaneously with the key bolt, so that the opening of the door by such person will be facilitated.

The invention also aims to provide simple, 30 effective mechanism, applicable to locks of different types, whereby two or more tumbler controlled bolts may be simultaneously retracted; to provide improved tumbler mechanism for the thumb bolts of a communicating door lock, or for other bolts having 35 the same general location relative to each other; and to improve the general construction and operation of devices of the class to which my invention relates.

To these and other ends, the invention 40 consists in the novel features and combinations of parts to be hereinafter described and claimed.

In the accompanying drawings, Figure 1 is an elevation of a lock embodying my improvements, with the cap plate removed, the thumb bolts and key bolt being in retracted position; Fig. 2 is an elevation of the lower part of the lock, showing one of the thumb bolts protracted; Fig. 3 is a similar view, 45 with one thumb bolt omitted and the other in protracted position; Fig. 4 is an elevation of the main part of the lock, showing the key bolt and one of the thumb bolts protracted, the other thumb bolt being omitted; Fig. 5 is a view similar to Fig. 4, showing

both thumb bolts partly retracted by the partial retraction of the key bolt; Fig. 6 is a section on line 6—6 of Fig. 1; Fig. 7 shows one of the thumb bolts in detail; Fig. 8 shows the other thumb bolt in detail; Fig. 9 shows the thumb bolt tumbler in detail; and Fig. 10 is a detail of one of the thumb bolt hubs.

Referring to the drawings, 20 is a case of usual type, and 21 and 22 are independent 65 thumb bolts. These thumb bolts have the customary relation to each other in so far as their shank portions extend alongside each other, while their heads are offset vertically. The bolt 21 is adapted to be protracted and retracted by a thumb bolt hub 23, and the bolt 22 is adapted to be protracted and retracted by the hub 24. Referring to Figs. 7 and 8, it will be noted that the shanks 21^a, 22^a of the respective bolts are 70 so formed as to create between said bolts a recess for a tumbler 25 common to said bolts. This tumbler is pivoted in the case on a post 26, and its main portion is interposed between the shanks 21^a, 22^a, and is provided 75 with a lug 27 at its upper edge, adapted to coöperate with stumps 21^b, 22^b, projecting inward from the shanks of the respective bolts. At its extremity, the tumbler 25 is provided with a tail or sweep 28, adapted 80 to be engaged by both hubs 23 and 24, so that said tumbler may be released from engagement with the bolt stumps or fences 21^b, 22^b, by actuation of either hub. The hub 23 is provided with a nose 23^a (Fig. 10) 90 to coöperate with the tumbler sweep 28, and with a roll-back arm 23^b to coöperate with the roll-back notch 21^c of the bolt 21, and the hub 24 is similarly provided with a nose 24^a to coöperate with the sweep 28 and with 95 a roll-back arm 24^b to coöperate with the roll-back notch 22^c of the bolt 22. The stumps or fences 21^b, 22^b extend upward from the upper edges of the respective bolt shanks to a certain extent for a purpose 100 which will hereinafter appear.

Above the thumb bolts 21, 22 is a key bolt 29 adapted to be operated by a key inserted in a keyway 30, open at opposite sides of the case. This bolt is provided with a 105 stump or fence 31, with which coöperates a tumbler 32, pivoted on a post 33. In practice, the bolt 29 will have a certain number of tumblers in addition to the tumbler 32, but this feature need not be discussed in 110

further detail. The tumbler 32 is provided with a spring 34, and with a depending arm 35, adapted to engage and coöperate with an arm 36, forming an upward extension of the thumb bolt tumbler 25. In other words, the tumblers 25 and 32 respectively are formed as elbow levers, and one arm of each lever is adapted to engage an arm of the other lever.

10 Secured to the shank of the key bolt 29 is a movable thumb bolt retracting member, preferably comprising a lever 37, pivoted on the bolt 29 at 38. This lever 37 is acted on by a spring 39 which urges the free end of said lever in a downward direction toward the thumb bolts. The lever 37 is suitably formed to clear the tumblers 25 and 32 in the operations hereinafter described, and its lower free end is provided with a lateral projection 40, adapted to engage either or both of the tumbler stumps 21^b, 22^b of the respective thumb bolts.

The operation of the lock is substantially as follows: When the parts are in the position shown in Fig. 1, the thumb bolts 21, 22 may be independently operated by the hubs 23, 24 respectively. When it is desired to prevent guests or others from opening the door from either side, the key bolt 29 is thrown, from either side of the door, by the maid or other possessor of the proper key. The manipulation of the thumb bolts will then be of no effect in opening the door. Supposing, now, that when the maid, or other authorized person, desires to unlock the door, both of the thumb bolts are in protracted position, the key bolt in being retracted, will retract both thumb bolts. This is due to the fact that when the key bolt is protracted, the extremity 40 of the lever 37, will be held by the spring 39 in line with the tumbler stumps 21^b, 22^b so that as the lever 37 is moved rearwardly by retraction of the key bolt, it will retract both thumb bolts. The release of the thumb bolts for this retracting movement is produced by the tumbler 32 of the key bolt which, in being raised by the key, is so actuated that its arm 35 contacts with and shifts the arm 36 of tumbler 35 to release the latter tumbler. In other words, when the tumbler mechanism of bolt 29 is released, the tumbler of the thumb bolts is likewise released, so that as the key bolt is retracted, the thumb bolt retracting member 37 may freely retract the thumb bolts. When the key bolt is projected, the spring 39 is permitted to act freely on the lever 37, and hold it in horizontal alignment with the tumbler stumps of the thumb bolts, but when the key bolt is retracted the arm 35 of the tumbler 32 will abut a shoulder 37^a on the lever 37 (as said tumbler is moved by its spring into locking engagement relative to the fence 31, as the bolt is retracted), whereby the lever 37 is swung upward suffi-

ciently to clear the stumps of the thumb bolts and permit a free protraction of said bolts.

In case any one of the thumb bolts is in protracted position when the key bolt is retracted, the lever 37 instead of engaging both tumbler stumps of the thumb bolts will only engage the stump of the projecting bolt, whereby such bolt will be retracted individually. In other words, the key bolt will retract either thumb bolt, or both of the same, whereby the mere retraction of the key bolt will open the door, in spite of the projection of a thumb bolt at one side of the door, or at the other side, or at both sides.

I have not attempted to illustrate and describe the numerous modifications of the construction which may be adopted within the scope of the claims.

What I claim is:

1. In a lock, the combination of a pair of thumb bolts, a key controlled bolt, and a lever carried by said latter bolt to engage and thereby retract either or both of the thumb bolts as the key bolt is retracted; substantially as described.

2. In a lock, the combination of two bolts, and a movable member carried bodily by one bolt, and adapted to engage the other bolt to retract such other bolt as said first bolt is retracted; substantially as described.

3. In a lock, the combination of two bolts, and a movable lever carried by and movable bodily with one bolt, and adapted to engage the other bolt to retract such other bolt as said first bolt is retracted; substantially as described.

4. In a lock, the combination of a thumb bolt, a key bolt, tumbler mechanisms for said bolts, means for releasing said tumbler mechanisms simultaneously, and means for retracting the thumb bolt as the key bolt is retracted; substantially as described.

5. In a lock, the combination of a thumb bolt, a key bolt, tumbler mechanisms for the respective bolts, means associated with the key bolt for releasing said tumbler mechanisms simultaneously when the key bolt is operated, and a movable member bodily carried by said key bolt, and adapted to retract the thumb bolt as the key bolt is retracted; substantially as described.

6. In a lock, a thumb bolt, a key bolt, tumblers for the thumb bolt and key bolt respectively, adapted to engage each other, whereby the actuation of the key bolt may free the thumb bolt and means for retracting the thumb bolt as the key bolt is retracted; substantially as described.

7. In a lock, a pair of thumb bolts, a common tumbler therefor, a key bolt, a tumbler for said key bolt adapted to operate the common tumbler for said thumb bolts, and means for retracting the thumb bolts as

the key bolt is retracted; substantially as described.

8. In a lock, the combination of two bolts arranged side by side, and a tumbler for both of said bolts interposed between the same; substantially as described.

9. In a lock, the combination of thumb bolts, a common tumbler therefor interposed between said bolts, a key bolt, and a tumbler for the key bolt adapted to engage and release the thumb bolt tumbler; substantially as described.

10. In a lock, the combination of thumb bolts having stumps, and a key bolt having means to engage said stumps, and thereby retract said thumb bolts; substantially as described.

11. In a lock, a thumb bolt having a stump, a tumbler coöoperating with said stump, a second bolt, and means carried by said second bolt to engage said stump and retract said first bolt; substantially as described.

12. In a lock, the combination of two bolts having their shanks arranged side by side, inwardly projecting stumps or fences on the shanks of the respective bolts, and a pivoted tumbler having a part interposed between the shanks of said bolts and coöperating with both of said stumps or fences; substantially as described.

13. In a lock, the combination of thumb bolts having their shanks arranged side by side, a common tumbler for said bolts interposed between said shanks, tumbler stumps on the respective bolts, means for operating the respective bolts, a key bolt, a spring pressed lever bodily movable with said key bolt and adapted to engage either or both of said first named bolts to retract the same, and means for releasing the tumbler of said first named bolts; substantially as described.

14. In a lock, the combination of two bolts, one located above the other, and a yielding latch device carried by one bolt for engaging and retracting the other bolt; substantially as described.

15. In a lock, the combination of a case, two bolts having portions of their shanks in horizontal alinement, stumps on said bolts, and a tumbler to engage both of said stumps arranged flatwise between the opposing side faces of said shank portions; substantially as described.

In witness whereof, I have hereunto set my hand on the 2d day of December, 1913.

ALBERT A. PAGE.
